UNITED STATES PATENT OFFICE.

LUTHER T. PEARSALL AND WARREN ELSEY, OF PITTSBURGH, PENNSYLVANIA.

DRIVE MECHANISM FOR PADDLE WHEELS OF BOATS.

Application filed April 18, 1923. Serial No. 632,963.

To all whom it may concern:

Be it known that we, LUTHER T. PEARSALL and WARREN ELSEY, residing at Pittsburgh, in the county of Allegheny and State of Pennsylvania, citizens of the United States, have invented or discovered certain new and useful Improvements in Drive Mechanism for Paddle Wheels of Boats, of which improvements the following is a specification.

Our invention relates to improvements in drive mechanism for the paddle wheels of boats; it concerns the communication of power through a rotary shaft to the rotary paddle wheel, and has particularly to do with making flexible the power-transmission mechanism, so as to provide for an appreciable and relatively great movement as between the boat structure and the propelling member. Such movement is an incident to service, and, particularly in the case of a stern-wheeled boat, there is often a very appreciable displacement of the paddle wheel relatively to the hull of the boat. This may occur, for example, when the wheel strikes the bottom of the shallow stream which the boat may be navigating. Our invention is particularly applicable to a stern-wheeled boat. The object is that which has been indicated, to provide transmission mechanism, including rotary shaft and gearing, which shall be flexible to meet service conditions and yet efficient and durable in the transmission of power.

In the accompanying drawings Fig. I is a view in side elevation, and Fig. II a view in plan, of a boat having our invention applied to it. In Fig. II the paddle wheel is, for the sake of clearness, shown in axial and horizontal section. In these two figures the outlines of the boat and its superstructure are sufficiently developed to indicate how the engine and the power transmission parts are arranged within it. Figs. III and IV are views to larger scale, showing in side elevation and in plan from above, so much of the power-transmission mechanism as immediately engages the paddle wheel. Fig. V is a view to still larger scale, showing in elevation the shaft of the paddle wheel, and, in section the anchorage by which adjustment is made between the paddle-wheel shaft and

the power-transmission mechanism. Figs. VI and VII show in side elevation and in plan from above (and this also to larger scale than Figs. III and IV) a detail of a support for the driving mechanism.

Referring, first, to Figs. I and II, the boat is indicated in outline by the numeral 1, its paddle wheel by 2. 3 is the engine and 4, 10 its power-transmission shaft. The paddle wheel 2 turns in bearings borne by brackets 22 which extend from the hull of the boat. The engine may be of any type preferred, capable of imparting torque to the shaft 4, 10. We show an internal-combustion engine, 65 of modified Diesel type, for that is the engine which we have adopted for installation. The shaft 4, 10 carries a beveled pinion 5 which meshes with a beveled gear-wheel 6 (cf. Fig. IV), with which the axle 7 of the 70 paddle-wheel is equipped.

Between the engine shaft 8 (Fig. I) and the power-transmission shaft 4, 10 is a two-speed gear reduction with sliding pinions. This is a well-known mechanical part, and 75 we have deemed detailed showing of it to be unnecessary. The casing which contains it is indicated at 9.

The power-transmission shaft is made in three sections, the anterior, which is unnumbered, the medial, to which the numeral 4 is immediately applied, and the posterior, 10. The three sections are united by flexible couplings 11 and 12. The forward section is driven from the engine shaft through the 80 gear reduction mechanism contained within casing 9. The shaft section 10 at its posterior end carries immediately the beveled pinion 5. The shaft section 4 is carried by the flexible couplings 11 and 12, between which 90 it extends free.

A bridge member 13 extends between and at its ends is supported by the boat on one hand and the axle of the paddle wheel on the other. Its particular construction will 95 best be understood on considering particularly Figs. III and IV. It is at its rear end bifurcated; its bifurcations are journalled to the axle 7 of the paddle wheel; at its forward end it is equipped with a roller 14, 100 which runs in a channel extending horizontally and transversely upon the stern of the

boat. This channel may take the form of a special casting 15 secured to the boat structure. The periphery of the roller 14 is spherical, or substantially so, as is best indicated in Figs. VI and VII.

The drawings do not show the structure in this detail, but it will be understood: the paddle wheel is at its ends journaled in arms which extend rearward on either side, from the hull of the boat, and, as is well known, there is necessarily a certain amount of flexibility of this mounting of the paddle-wheel to the hull of the boat, and the structure of the nature indicated is designed with such flexibility in view.

Now it will be apparent that the bridge member 13, pivoted in vertical plane to the axle of the paddle-wheel, and equipped at the base which rests upon the hull of the boat, with a spherically rimmed roller running in a straight-walled channel, is freely responsive to every displacement of the paddle-wheel relative to the hull of the boat,—whether that displacement be in straight-line movement or torsional.

The shaft section 10 is, as is best shown in Figs. III and IV, mounted on bridge member 13, in the guide bearings 16 and 17.

The beveled gear wheel 6 is secure upon axle 7 of the paddle-wheel. The bifurcated ends of bridge member 13 include the gear wheel. The journal bearings 18 and 19 carried by the arms of the bifurcated bridge member, and within which axle 7 turns, encircle the axle 7 upon opposite sides of the hub of gear wheel 6. The bevel-gear pinion 5 borne by shaft section 10 extends into the space between the bifurcations of the bridge member, and there engages the bevel-gear wheel 6. Means are provided for holding pinion 5 in full and firm intermeshing engagement with gear wheel 6. The structure will be understood on comparing Figs. IV and V.

Upon axle 7 is rigidly secured a collar 20. Set screws 21 extend from casing 19 and, through a suitable interposed block, bear upon the rotating collar 20. As these screws are tightened and loosened the thrust under which pinion 5 is held to engagement with gear wheel 6 is increased and diminished.

The problem is a drive mechanism which includes a rotary transmission shaft and which is flexible to meet conditions of service. We solve the problem by providing the bifurcated bridge member with floating base, by mounting the transmission shaft on this bridge member, with flexible coupling connecting it to the source of power, and by providing a collar upon the axle of the paddle wheel against which purchase is had for the thrust holding the parts of the bevel-gear in mesh. The shaft section 4, extending as it does free between the flexible cou-

plings which engage it at opposite ends and so carry it, cannot in consequence of relative displacement of its ends be subjected to any strain.

We claim as our invention:

1. In a power-driven boat the combination with the hull of the boat, brackets extending from the hull, and a paddle-wheel rotatable in bearings borne by said brackets, of an engine having a rotary power shaft carried by the boat, a floating bridge member spanning the space between the hull and paddle-wheel axle and sustained by said paddle-wheel axle, a transmission shaft journaled upon said bridge member, means for imparting rotation from the engine shaft to the transmission shaft, and means for imparting rotation from the transmission shaft to the paddle-wheel axle.

2. In a power-driven boat the combination with the hull of the boat, brackets extending from the hull, and a paddle-wheel rotatable in bearings borne by said brackets, of an engine having a rotary power shaft carried by the boat, a bridge member resting at one end upon the axle of the paddle-wheel and at the other end making a floating bearing upon the hull of the boat, a transmission shaft carried in bearings upon said bridge member, means for transmitting rotation from the engine shaft to the transmission shaft and means for imparting rotation from the transmission shaft to the axle of the paddle wheel.

3. In combination with a boat carrying a paddle wheel in bearings subject to displacement with respect to the hull of the boat, an engine having a rotary power shaft carried by the boat and with respect to which also the paddle-wheel bearings are subject to displacement, a bifurcated bridge member provided in its bifurcations with bearings through which it rests upon the axle of the paddle wheel and provided at its opposite end with a roller having a spherical tread and arranged within and resting within a channel-formed upon the boat structure and extending in general parallelism with the paddle-wheel axle, a transmission shaft section mounted in bearings upon said bridge member, means including a flexible coupling for transmitting rotation from said power shaft to said shaft section, and rotation-transmitting connection between said shaft section and the axle of the paddle wheel.

4. In combination with a boat carrying a paddle wheel and an engine with a power shaft borne by the boat and with respect to which the bearings for the axle of said paddle wheel are subject to displacement, a bifurcated bridge member provided with bearings through which the axle of the paddle wheel extends and within which said axle rotates, a shaft borne by and rotatable in journals upon said bridge member and

through bevelled-gears engaging the axle of
said paddle wheel, a shoulder upon the axle
of the paddle wheel, and thrust mechanism
borne by said bridge member and adapted
5 to engage said shoulder and by such en-
gagement to hold the wheels of said bevelled-
gearing in mesh.

In testimony whereof we have hereunto
set our hands.

LUTHER T. PEARSALL.
WARREN ELSEY.
